UNITED STATES PATENT OFFICE.

JOSEPH P. SORENSEN AND ROYDEN THORNBURG, OF SAN FRANCISCO, CALIFORNIA.

POOL-TABLE.

1,210,864.

Specification of Letters Patent. Patented Jan. 2, 1917.

Application filed June 8, 1914. Serial No. 843,741.

To all whom it may concern:

Be it known that we, JOSEPH P. SORENSEN and ROYDEN THORNBURG, citizens of the United States, residing at San Francisco, in the county of San Francisco, State of California, have invented a new and useful Pool-Table, of which the following is a specification in such full and clear terms as will enable those skilled in the art to construct and use the same.

This invention relates to a pool table and its object is to deliver the balls claimed by each player in separate pockets thereby enabling each player to know just how many balls he has obtained without the necessity of gathering the balls up after each play. The above object is attained by means of an electrically operated apparatus which is shifted by each player so that the balls played by him will be discharged in his pocket.

An embodiment of the invention is shown in the drawing in which the same reference numeral is applied to the same portion throughout, but we are aware that there are many modifications thereof.

Figure 1 is a side elevation of the table, each side appearing substantially the same as in Fig. 1, Fig. 2 is a plan view of the table with the cushions and top removed therefrom, Fig. 3 is a vertical sectional view of the table on the line 3—3 Fig. 2, Fig. 3^A is a broken perspective view partly in section of the distributing apparatus adjacent the center of the table. Fig. 4 is a vertical sectional view on the line 4—4 Fig. 2, Fig. 5 is an end view of the table, each end appearing substantially the same as in Fig. 5, Fig. 6 is a diagrammatic view of the electrical wiring of the table, Fig. 7 is a plan view of the table showing the lower set of chutes which deliver the separated balls to the individual pockets, Fig. 8 is a side elevation of the cup which sends the balls to the individual chutes, Fig. 9 is a plan view of one of the relay armatures, Fig. 9^A is a side elevation of one of the relays showing the relation of its contact making devices. Fig. 10 is a plan view of one of the contact brushes.

The numeral 1 represents the table legs, said legs being connected by means of stringers 2 and connected at their upper ends with a rectangular frame work 3, which supports cushions 4 and top 5. The cushions and top are connected with each other

and are removably secured to the frame work 3. At the bottom of the frame work 3 there is a floor 6 which floor affords a support for the six inclined troughs 7 to 12 inclusive, said troughs extending from the usual pockets at the corners and sides of the table to the central opening in the floor 6.

The stringers 2 connecting the lower portion of the table legs support a floor 13 upon which floor the electrical apparatus and mechanical apparatus for the operation of the ball switch is installed. Near the center of the floor 13 there is an inverted U shaped frame 14 which rests upon the floor and forms a support for a block 15. This block 70 has a plurality of members 16 which extend upwardly through the floor 6 to close the space between the four chutes 17 to 20 inclusive.

The chutes 17 to 20 inclusive are supported at one end on the block 15 and at the other end each chute is supported on a short post as indicated at 21, 22, 23 and 24, the ends of the chutes projecting through the doors 25 to 28 respectively. The doors 25 to 28 inclusive are hinged at one end as indicated at 29 and 30 and a suitable catch, not shown, is used to hold them closed. On each door a cup 31 is secured adjacent the opening through which the chutes project, said cup being for the purpose of receiving the pool balls as they may be discharged through the chute leading thereto.

The members 16 form a circular chamber within which a cylindrical cup 33 having an inclined bottom is mounted, said cup having an opening 33' on one side for the discharge of the balls rolling thereinto to any one of the chutes 17 to 20 inclusive. The cup 33 is mounted upon a vertical shaft 34, 95 which shaft has a bearing 35 on the floor 13.

The shaft 34 is provided with a gear wheel 36, which gear wheel is in mesh with a worm 37 on the shaft 38 of the motor M. The worm wheel shaft is also provided with a bearing 39 mounted upon the floor 13. Also mounted on the shaft 34 is a fiber disk 40. This disk has a ring 41 thereon which ring is cut at 42 and in contact with which ring the brushes 43, 44, 45 and 46 operate. The brushes 43 to 46 inclusive are secured to the floor 13 in any suitable manner and are in turn connected with the electric wiring in a manner that will be explained later.

Mounted on the side framing 3 of the ta- 110

ble are the push buttons 47, 48, 49 and 50, said push buttons being for the purpose of enabling any player to set the apparatus so that the balls played by him into the pockets in the pool table will be discharged into his individual receptacle.

In order to enable the proprietor to disconnect the electrical apparatus at will the door 25 is provided with a suitable two point switch 51, which switch is connected with the electric wiring system in a well known manner as will be explained in the wiring diagram.

In order that the motor may be operated four relays 52, 53, 54 and 55 are mounted upon the floor 13 and connected with the electrical circuits. Another relay 56 is also mounted upon the floor 13 for the purpose of closing the circuit on the pilot light 57 to enable the players to know when a play may be made, said light indicating that the apparatus is in motion.

In order to enable all of the players to see when the apparatus is moving an extension of the wires carrying the current is made to each side of the table so that one of the lights 57 shows at each side and end of the table.

In the wiring diagram, Fig. 6, 34 indicates the shaft carrying the disk 40 upon which disk the ring 41 is mounted. The brushes are indicated at 43 to 46 inclusive with which brush wires 60, 61, 62 and 63 are connected, each of said wires extending to the relays. The relays 52 to 55 respectively are of a common form.

In Figs. 9 and 9^A the parts of the relays are illustrated, 52 indicating the coil, 64^a a base upon which the coil is mounted, which base carries a pivot rod 64^b for the armature 64^a, said armature having a rearwardly extending portion 64 which engages the contact point 64' when the armature is raised by the magnet 52. The wires from the brushes 43 to 46 inclusive extend to the relays 52 to 55 inclusive from the opposite sides of which wires 70, 71, 72 and 73 extend to the push buttons. From the opposite side of the push buttons, wires 74, 75, 76 and 77 extend to the wires 78, 79, 80 and 81, all connected together by means of the wire 82, which wire extends to the battery B. The numerals 65, 66 and 67 indicate the armatures of the remaining relays, there being one relay for each player and set of individual troughs.

Each of the relay armatures cuts out the adjacent push button whenever that particular push button has been closed, so that when once one of the push buttons is closed the relay will hold the circuit closed until it is broken at some other place, as will be later explained. Extending from the opposite side of the battery is a wire 83 connected into the switch 51, a wire 85 extending to

the motor M from the opposite side of which the wire 86 extends to the shaft 34, a wire 87 connecting the ring 41 with the shaft 34.

In order to prevent irregular currents from the motor from interfering with the operation of the relays 52 to 55 inclusive, a shunt relay 56 is provided across the motor. This relay has wires 88 and 89 connecting it with the wires 85 and 86. It operates an armature 90, which armature connects the wire 91 with an extension of the wire 82, said wire 91 extending to the lamps 57, and it at the same time provides the path for the current to hold the armatures of the relays up. On the opposite side of the lamps from the wire 91, a wire 92 extends to the wire 85.

The result of the foregoing construction is that whenever one of the push buttons closes a circuit that its relay armature will be picked up and the circuit will remain closed until the motor has turned the shaft 34 and assembled parts to the desired position, which is that position determined by the particular relay circuit energized and its particular brush 43 to 46 whichever may happen to be passing current. At the same time that the push button is operated the relay 56 will be operated and the lamps 57 will glow, thus indicating that the apparatus is in motion and that a play is not to be made. As soon as the opening in the ring 41 reaches the brush passing current the circuit will be broken and both of the relays will drop their armatures and the motor will stop, thus leaving the segregating cup in the desired position to deliver the balls played to the proper player. As soon as the relays drop their armatures the lights will go out indicating that the apparatus is ready for the play to take place.

Having thus described our invention what we claim as new and desire to secure by Letters Patent of the United States, is as follows, modifications within the scope of the claims being expressly reserved:

1. In a pool table, the combination of a table having a plurality of pockets, a distribution apparatus, troughs to deliver the balls played into the pockets of the table to the distribution apparatus, an electric motor for operating the distribution apparatus, electric circuits for operating said motor including a push button for individual players, a relay for holding the motor circuit closed after the push button has been operated until the distribution apparatus has moved to a position corresponding to that push button, and other troughs to deliver the balls to the individual players after the distribution has been effected.

2. In a pool table, a table having a plurality of pockets therein, a central distribution compartment, troughs to deliver the balls played into the pockets of the table to

- the distribution compartment, a plurality of individual compartments, means in the distribution compartment to distribute the balls played to the several individual compartments, a plurality of troughs leading from the distribution compartments to the individual compartments, means to move the distribution apparatus to deliver the balls to the individual players, means whereby 5 a number of players may control the ball distribution apparatus, and a relay to prevent the ball distribution apparatus from being stopped after it has been set in motion and until it has completed the desired 10 change.
3. In a pool table, a table having a plurality of pockets, a central compartment having a movable distribution apparatus therein, troughs leading from the pockets 15 of the table to the distribution compartment, other troughs to deliver the distributed balls to the individual players, electrical means to operate the distribution apparatus, means under the control of a number 20 of players for operating said distribution apparatus, means to indicate the fact of motion of the distribution apparatus, and 25
- a relay to prevent the stoppage of the motor until a given change in the distribution apparatus has been made when it has once 30 been set in motion.
4. A pool table comprising a table having pockets, a plurality of troughs extending from the pockets to a centrally placed compartment, means in said compartment to 35 distribute the balls played, a second series of troughs extending from the central compartment, receptacles to which the latter troughs lead, an electric motor for operating the distribution apparatus, electric circuits 40 for different players whereby each may set said apparatus to deliver the balls to his individual receptacle, and means on each side of the table to indicate when the distribution apparatus is in motion.

In testimony whereof we have hereunto set our hands this 22nd day of May, A. D. 1914, in the presence of the two subscribed witnesses.
